(57) **CLAIM**

The design for a convertible top, as shown and described.

DESCRIPTION

FIG. 1 is a top left side perspective view of the convertible top;

FIG. 2 is a top right side perspective view of the convertible top;

FIG. 3 is a front side elevational view of the convertible top;

FIG. 4 is a rear side elevational view of the convertible top;

FIG. 5 is a right side elevational view of the convertible top;

FIG. 6 is a left side elevational view of the convertible top;

FIG. 7 is a top plan view of the convertible top;

FIG. 8 is a bottom plan view of the convertible top;

FIG. 9 is a top rear left side perspective view of the convertible top in the folded position;

FIG. 10 is a top left side perspective view of the convertible top in the folded position;

FIG. 11 is a top rear right side perspective view of the convertible top in the folded position;

FIG. 12 is a top right side perspective view of the convertible top in the folded position;

FIG. 13 is a front side elevational view of the convertible top in the folded position;

FIG. 14 is a rear side elevational view of the convertible top in the folded position;

FIG. 15 is a right side elevational view of the convertible top in the folded position;

FIG. 16 is a left side elevational view of the convertible top in the folded position;

FIG. 17 is a top plan view of the convertible top in the folded position; and,

FIG. 18 is a bottom plan view of the convertible top in the folded position.

Portions of the vehicle roof and convertible top are shown in broken lines for illustrative purposes only and form no part of the claimed design.

1 Claim, 14 Drawing Sheets
